UNITED STATES PATENT OFFICE.

CHRISTIAN PFEFFERKORN, OF SANDUSKY, OHIO.

AWNNG.

1,279,585.

Specification of Letters Patent. Patented Sept. 24, 1918.

Application filed February 28, 1916. Serial No. 80,812.

To all whom it may concern:

Be it known that I, CHRISTIAN PFEFFERKORN, a citizen of the United States, and a resident of Sandusky, county of Erie, and 5 State of Ohio, have invented a new and useful Improvement in Awnings, of which the following is a specification, the principle of the invention being herein explained and the best mode in which I have contemplated applying that principle, so as to distinguish it 10 from other inventions.

My present invention relates to an awning or canopy adapted to be used on windows or the like, and has for its object the production of an awning which shades the window from both the front and sides and which may be entirely raised and folded so as to leave the window clear when in such folded position. In accomplishing this purpose it 15 has also been my object to provide an awning which shall cover the upper part of the window but shall not stand outwardly therefrom, and I have provided supporting means which are quickly removable so that the entire awning and support may be detached 20 from the window. To the accomplishment of the foregoing and related ends, said invention, then, consists of the means hereinafter fully described and particularly 25 pointed out in the claim.

The annexed drawing and the following description set forth in detail certain mechanism embodying the invention, such disclosed means constituting, however, but one 30 of various mechanical forms in which the principle of the invention may be used.

In said annexed drawing:

Figure 1 is a perspective view of my awning in its lower position as attached to a 40 window casing; Fig. 2 is a side elevation of the awning in its raised position; Fig. 3 is a front elevation of the awning in the same position as in Fig. 2; Fig. 4 is a perspective view of one of the side supporting members 45 partially showing the supporting bracket and the retaining rod; and Fig. 5 is a perspective view of part of the supporting member showing a second method of mounting.

The present awning consists of a fabric 50 portion 1 having triangular side pieces 2 attached to the edges 3 of the same. These side portions extend along part of the edges of the main portion, leaving a plain rectangular section 4 of the fabric extending above

the side pieces. The lower edges of the main 55 portion and the side pieces are attached to a supporting bracket 5 in any suitable manner, in the present construction the awning having a hem through which the supporting bracket is forced. The top of the awning is 60 adapted to be attached to the window casing in any suitable fashion, such as by means of a rod 6 which is placed in a hem in the fabric, and the rod may be attached to the casing by means of flanged nuts 7 which are 65 threaded onto bolts 8 formed integral with small brackets 9, attached to the window casing. The means used for raising the awning, consist of ropes 11 attached to the supporting bracket and which are brought up 70 on the under side of the awning to a point approximately at the top of the triangular section and thence outwardly through eyelets 12 to the top of the awning and through other eyelets 13 to pulleys 14 which are attached to the window casing 10, the ropes thence hanging down and being adapted to 75 be fastened in the usual manner, as to a cleat 15.

The supporting bracket is pivotally attached at the ends to clips 16 which are slidably mounted upon rods 17 attached to the window casing at the sides thereof. These rods are held at the top and bottom in eyelets 25 and have a bent-in portion 18 at one 80 point of their length which will be attached to the casing by means of a screw or like fastening means 19. This bent-in portion serves the purpose of preventing the clips 16 from rising above a certain point which will 85 be predetermined so that the awning in its raised position will approximately uncover the entire window. Other clips 20 to which a cross rod 24 is pivotally attached, will be 90 slidably mounted upon the upper portion of the rod, above such bent-in portion, and this second rod serves to retain the upper part of the fabric in a substantially vertical position when the awning is lowered, and in this 95 position will lie just at the top of the side portions of the awning. A second form of supporting member is shown in Fig. 5 in which a straight rod 26 is used and this is held in a bracket 27 by means of a set screw 28 which is threaded in a boss on one side 100 of the bracket. This bracket is attached to the window casing by screws or the like and serves as does the bent-in portion 18 to limit

the downward movement of the rod 24 and the upward movement of the bracket 5 and the clips 16.

The operation of the present awning is thought to be so clear that a detailed description is not necessary, but by using the slidably mounted rod it has been found practical to make an awning giving all the advantages of the former type of awning which has the side portions and yet which shades the entire window when lowered and may still be raised so as to uncover the entire window when in its raised and folded position. Further, the present awning extends outwardly from the window only a limited distance, and is much less liable to be torn loose by the wind than if the awning were made so as to fold up to clear the entire window. In raising the awning the supporting bracket will first be pivoted about the clips and will be folded in toward the window frame and in this position will rest just below the cross rod. Further movement serves to raise the entire awning up in its folded position, the supporting bracket contacting the cross rod and raising the same. The side supporting members are quickly attached and detached from the window casing and the whole awning may be put up or taken down in a very short time as it is only necessary to loosen the two nuts which hold the supporting rods to the window casing.

It will be seen that the present awning combines the advantages of the older, fixed type of awning with that of the roll type, and yet has the disadvantages of neither. In the roll type of awning it has heretofore been found impracticable to use the side portions which are necessary to make an awning satisfactory, while the older fixed type of awning has a support which pivots so as to allow the awning to be folded up, but the older type of awning has the disadvantage that in the long window, to entirely uncover the window in its raised position, the supporting bracket has to extend so far

out from the window that the awning is unsightly in appearance and easily torn down by the wind.

50

Other modes of applying the principle of my invention may be employed instead of the one explained, change being made as regards the mechanism herein disclosed, provided the means stated by the following 55 claim or the equivalent of such stated means be employed.

55

I therefore particularly point out and distinctly claim as my invention:—

In an awning for windows and the like 60 the combination of the awning fabric consisting of a main portion, and side portions attached to the lower part of the edges of said main portion, and supporting means for said fabric consisting of two removably 65 mounted rods attached to the window casing, said rods having a bent-in portion adapted to be securely fastened to the casing, clips slidably mounted on said rods below said bent-in portion, a supporting 70 bracket pivotally attached to said clips, a second pair of clips slidably mounted on said rods above said bent-in portion, a rod attached to said second pair of clips, said rod being adapted to maintain the upper 75 portion of said awning in a substantially vertical position, said supporting bracket being adapted to hold said awning out from said window in its lower position, said bracket extending out from said window a 80 less distance than the length of the awning portion below said rod and being adapted when folded to fold against the casing below said rod so that upon raising it will contact and raise the same, thereby raising the 85 entire awning clear of said window, and means for raising the awning.
